UNITED STATES PATENT OFFICE.

WILLIAM J. LANE, OF POUGHKEEPSIE, NEW YORK.

DOOR-HANGER.

SPECIFICATION forming part of Letters Patent No. 433,009, dated July 29, 1890.

Application filed February 7, 1890. Serial No. 339,528. (No model.)

To all whom it may concern.

Be it known that I, WILLIAM J. LANE, of Poughkeepsie, in the county of Dutchess and State of New York, have invented a new and useful Improvement in Door-Hangers; and I do hereby declare that the following is a full, clear, and exact description of the same.

The invention hereinafter set forth is an improved sliding-door hanger. It is intended for the finer class of doors, such as the sliding doors of dwelling-houses. It pertains to that class of hangers in which the supporting-wheel runs upon a fixed rail and is mounted in a frame to which the door is adjustably attached and thereby suspended, so that the frame moves with the door and the adjustable attachment permits of vertical adjustment of the door, so that its relation to the floor over which the lower edge moves may be accurately determined. In hangers of this class the rail on which the door is suspended and moves is practically inaccessible after the wood-work of the door-frame is completed, and the adjusting devices must be accessible and therefore near the upper edge of the door. Economy and neatness of appearance require that the frame and adjoining devices be of simple construction; and there is another important point to be attained, which is that the door shall be readily attached to or removed from the frame. The frame, it will be understood, is first mounted on the track, with the wheel in place thereon and with the lower part of the said frame extending down through the slot in which the arms of the frame move back and forth.

One object specially sought to be attained by me is to provide special means whereby the door may be hooked upon the frame and so held while it is adjusted in height. In connection with the cheapness of manufacture it is necessary to take into consideration the kind of material that can be found on the market of ordinary and not special manufacture, and that may be without forging or expensive manipulations worked into proper shape for the frames. While I have had all these special objects in view and have produced a construction which meets all the requirements of the problem in a very satisfactory manner, I am well aware that the special construction

which I show is only one of a class in which the general features are included. The class is too extensive to admit of particular recognition; but I have, in view of what has been shown prior to my invention, limited my claim to the particular construction and combination hereinafter explained. This particular construction is illustrated in the accompanying drawings, in which—

Figure 1 represents a side elevation of the hanger in duplicate on a door and suspended from the rail. Fig. 2 shows the hanger in end view; Fig. 3, in section on line $x-x$ of Fig. 1.

In the drawings, A represents the track, which may be made of ordinary plain bar iron or steel set on edge and supported by suitable brackets. On this runs a wheel B, having a grooved periphery fitted to the rail. The wheel is mounted in bearings in the upper part or rails of the frame. The frame requires a considerable length to insure the proper strength and alignment and adjustability, and the rails (marked D) are therefore made longer than the diameter of the wheels would otherwise require. These rails are composed of two flat bars of steel d d. They are spaced apart by the interposed ends of the vertical bars e e', to which the door is attached. The rails are riveted to the upper ends of these bars and form with them a rigid frame. The rails are swelled out, as shown at f f, to give more lateral space for the wheel, which has ball-bearings g g to lessen the friction. The lower end of the bar e' (which is that farthest from the vertical edge of the door) is slotted and has a cross-pin h. This is fitted to engage with a slotted stud k, which is adapted to enter the slot in the bar. The slot in the stud is inclined upward from its open end, so that the stud k may be hooked over the pin h. The stud k is on the upper face of the inner end of the plate E, which is screwed to the door on the upper edge. At the other or outer edge of this plate is a threaded sleeve F. This has a flange on its lower end. The sleeve is fitted to a hole in the end of the plate, and this hole is rabbeted about the edge underneath to receive the flange on the sleeve, and by this flange the sleeve is loosely held after it has been inserted from underneath the plate. There are holes i made radially through the sleeve just

above the plate, in which a pin may be inserted for turning the sleeve. The lower end of the bar *e* is threaded to fit the interior thread of the sleeve. The frame being in place on the rail, the lower ends of the bars project centrally below the same, (the bars being offset around the track,) and the door may be attached readily by hooking the slotted stud over the pin in the bar *e'*. Then the threaded end of bar *e* is entered into the sleeve and the sleeve is turned to raise the door to any required height. The sleeves, being next to the edge of the door, are easily accessible and the operation of hanging the door very simple and easy. Plainly the form of the hook, as well as that of the sleeve, may be changed, equivalent forms of hook and screw connections being well known.

I claim as my invention—

A door-hanger consisting of an elongated frame *B*, an adjustable connection between one end of said frame and the attaching-plate, a pivoted connection between the other end of the frame and said plate, and a wheel or pulley *B*, journaled in ball-bearings to one side of the center of said elongated frame near the adjusting end, substantially as described.

In testimony whereof I have signed my name to this specification in the presence of two subscribing witnesses.

WILLIAM J. LANE.
